(57) **CLAIM**

The ornamental design for a utility radio frame, as shown and described.

DESCRIPTION

FIG. 1 is a front perspective view of a utility radio frame showing my design.

FIG. 2 is a right-side view of the utility radio frame of FIG. 1.

FIG. 3 is a left-side view of the utility radio frame of FIG. 1.

FIG. 4 is a top view of the utility radio frame of FIG. 1.

FIG. 5 is a bottom view of the utility radio frame of FIG. 1.

FIG. 6 is a front view of the utility radio frame of FIG. 1; and,

FIG. 7 is a rear view of the utility radio frame of FIG. 1.

The broken line showing of the radio body and speaker mesh represent portions of the design that form no part of the claim.
